US00D597608S

(12) **United States Design Patent**
Langan et al.

(10) **Patent No.:** **US D597,608 S**
(45) **Date of Patent:** **** Aug. 4, 2009**

- (54) **DRUG ADMINISTRATION SAFETY LABEL**
- (75) Inventors: **Amy Elizabeth Langan**, Glenview, IL (US); **Richard John Kruzyński**, Long Grove, IL (US); **John Anton Kollar**, Northbrook, IL (US); **Patricia Lynn Miyake**, Mundelein, IL (US); **Monique Lafayre Kruk**, Burlington, WI (US); **Mark Francis Wagner**, Gurnee, IL (US)
- (73) Assignee: **PharMEDium Services, LLC**, Lake Forest, IL (US)
- (**) Term: **14 Years**
- (21) Appl. No.: **29/318,375**
- (22) Filed: **May 19, 2008**
- (51) **LOC (9) Cl.** **19-08**
- (52) **U.S. Cl.** **D20/27**
- (58) **Field of Classification Search** **D20/10, D20/11, 13, 19, 22-24, 27, 40, 42, 99; 40/124.01, 40/124.02, 124.04, 124.09, 299.01, 310, 40/325, 326, 359, 360, 538, 541, 584, 591, 40/594, 600, 617, 638, 661.01, 661.09; 206/63.3, 206/534; 283/51, 56, 67, 71, 74, 75, 81, 283/99-101, 107-109, 114, 117; 428/40.1, 428/42.1-42.3, 914; 705/3; D19/1, 2, 10; D30/155**

See application file for complete search history.
